ATTORNEYS

UNITED STATES PATENT OFFICE.

GEORGE C. WERNER, OF BROOKLYN, NEW YORK.

SWITCH.

Application filed December 10, 1920. Serial No. 429,670.

To all whom it may concern:

Be it known that I, GEORGE C. WERNER, a citizen of the United States, and a resident of the city of New York, borough of Brooklyn, in the county of Kings and State of New York, have invented a new and Improved Switch, of which the following is a full, clear, and exact description.

This invention relates to the general class 10 of electric switches and has particular reference to an improvement in a double trip switch.

The invention contemplates for one of its 15 principal objects, the provision of a double switch provided with means which renders the same capable of either mechanical or electrical actuation.

Another purpose of the invention is to 20 provide a double trip switch which is extremely simple in its construction and method of operation, inexpensive to manufacture, highly efficient, and strong and durable in construction.

With the above recited and other objects 25 in view, some of which will appear hereafter, reference is had to the following specification, the appended claims, and the accompanying drawings, in which—

Figure 1 is a longitudinal sectional view 30 through a box or container for the switch.

Fig. 2 is a transverse sectional view taken approximately on the line 2—2 of Fig. 1.

Fig. 3 is a horizontal sectional view taken on the line 3—3 of Fig. 1.

Fig. 4 is a diagrammatic view of one use 35 to which the switch may be adapted.

Referring to the drawings by characters of reference, 10 designates a housing for the switch which may be of any suitable 40 construction other than that shown. The housing is provided with a removable cover 11 which constitutes the base upon which the switch elements are mounted. The switch includes two pair of contact members 45 comprising respectively the resilient embracing jaws 12, 12 and 13, 13 respectively carried by the bases 14, 14 and 15, 15. A vertically movable circuit closing member 16 carrying the blades 17, 17 is mounted on 50 the stem 18. The stem 18 is slidably mounted for vertical movement in the U-shaped bracket 19 and the upper end of said stem extends through an opening in the cover of the housing and is provided with a manipu-

lating knob or button 20. The stem is retained against rotation through the engagement of the pin 21 carried by the circuit closing member 16 in the slot 22 in the bracket. A coiled contractile spring 23 encircles the stem 18 and is positioned thereon between the lower arm 24 of the bracket and the circuit closing member whereby to normally exert a tension to effect the engagement of the blades 17 of the circuit closer with the contact elements 12, whereby to 65 bridge the same. The embracing jaws of the contact elements are disposed with their mouths in superposed relation whereby when the manipulating button 20 is operated to move the stem against the action of the spring 23, the blades 17 will be disengaged from the upper embracing jaws 12 and engage with the lower embracing jaws 13. In order to provide means for retaining the blades in engagement with the lower jaws 70 13, for bridging the same, against the action of the spring 23, use is made of a pivoted latch 25 which is mounted as at 26 to the free extremity of the lower arm 24 of the bracket. A convolute spring 27 normally effects the swinging of the latch to a position to engage and lock the member 16 in circuit closing relation with the lower jaws 13. The nose of the latch 25 is beveled as at 28, and the lower side of the circuit 75 closing member 16 is beveled as at 29 whereby said beveled surfaces will coact upon downward movement of the circuit closing member to automatically effect the locking of the latch. The switch is provided with a mechanical means for releasing the latch, and said mechanical releasing means comprises a lever 30 carried by the pivot 26. One extremity of the lever constitutes a finger 31 which engages the latch and the 80 opposite extremity 32 is connected to a shifting rod 33 which extends upwardly through the cover 11 and is provided with a button 34. A coiled contractile spring 35 surrounds the shifting rod and is positioned 85 between the button and the cover. By this arrangement it will be seen that upon depressing the button 34, against the action of the spring, the lever will be swung to a position to effect the disengagement of the latch 90 100 with the circuit closing member.

The electrical means for releasing the latch comprises an electromagnet 36 carried

by a leg 37 depending from the upper arm 38 of the bracket. The said electromagnet 36 is designed when energized to attract the latch 25 which assumes the rôle of an armature.

The switch is capable of many uses, but for the purpose of demonstrating one of its uses, the diagram illustrated in Fig. 4 has been used. This diagram represents a burglar alarm system which includes a primary actuating circuit 40 and a secondary alarm circuit 41. In this use of the switch, the primary actuating circuit includes the electromagnet 36, the battery 42 and a circuit closing button 43 which is normally held out of contact with the points 44 by the engagement therewith of the window sash 45. The primary circuit also includes the contact jaws 13, 13 which are bridged by the blades 17 when the alarm system is set. To initially set the alarm system the stem 18 is depressed to effect the bridging engagement of the blades 17 with the contact members 13, the armature or latch 25 engaging the circuit closing member 16 to retain the same in set position against the action of the spring 23. The secondary or alarm circuit 41 includes the bell 46, the contact members 12 and the battery 42. In this use of the invention, when the window sash is raised and the circuit closing button 43 is released the same will bridge the contact points 44 to close the primary or actuating circuit 40. When the circuit 40 is closed, the electromagnet 36 will be energized and will attract the armature 25 to effect its disengagement to release the circuit closing member 16. The spring 23 will shift the stem 18 and the blades 17 into bridging engagement with the contact members 12, thereby closing the secondary or alarm circuit 41 to cause a continuous or constant ringing of the bell 46, until the button 20 is again depressed to break the secondary circuit. The device may also be used in call systems where the electrical release of the retaining means may be used to good ad-

vantage as a signal to acknowledge the receipt of a call by the receiver of the same.

While there has been illustrated and described a single and preferred embodiment of the invention, no limitation is necessarily made to the precise structural details, nor the particular use set forth, as it is understood that variations and modifications in the structure and use which fall within the scope of the appended claims may be resorted to when found expedient.

I claim:

1. A switch comprising two pairs of contact elements, a common circuit closing member manually shiftable to engage and bridge one pair of contacts, automatic means for effecting normal bridging engagement with the other pair, a pivoted latch adapted to automatically engage and to coact with said member for retaining the same in engagement with said latter pair of contacts, independent means for effecting the release of said latch mechanically or electrically comprising a lever pivoted adjacent said latch and manually operable to release the same, and an electromagnet adjacent said latch adapted when energized to attract the same for moving it to releasing position. 75

2. A switch comprising two pairs of contact elements, common circuit closing members manually shiftable to engage and bridge one pair of elements, a pivoted latch to engage with the member for retaining it in engagement with said pair of contacts, electromagnetic means for releasing the latch, means for moving the circuit closing member to normal position in contact with the other pair of contact elements, and a pivoted, manually operated lever normally disposed adjacent the latch member, said lever being independent of the electromagnetic means and adapted when operated to attract the latch member, said lever providing separate means whereby the latch may be released independently of the action of the electromagnetic means. 90

GEORGE C. WERNER.
